CLAIM

The ornamental design for a bottle cap remover, as shown and described.

DESCRIPTION

FIG. 1 is a bottom, front, left side perspective view of a bottle cap remover in accordance with the present invention;

FIG. 2 is a front view of the bottle cap remover shown in FIG. 1;

FIG. 3 is a rear view of the bottle cap remover shown in FIG. 1;

FIG. 4 is a top view of the bottle cap remover shown in FIG. 1;

FIG. 5 is a bottom view of the bottle cap remover shown in FIG. 1;

FIG. 6 is a left side view of the bottle cap remover shown in FIG. 1; and,

FIG. 7 is a right side view of the bottle cap remover shown in FIG. 1.

The long and short broken lines around the outside edges in FIGS. 1, 2, and 3 that define the bounds of the claimed design form no part thereof. The features shown in evenly spaced broken lines are included to show portions that form no part of the claimed design.
